By Benj. Arnold Atty.

UNITED STATES PATENT OFFICE.

JAMES MUIRHEAD, OF OLNEYVILLE, RHODE ISLAND.

WATER-CLOSET.

SPECIFICATION forming part of Letters Patent No. 288,655, dated November 20, 1883.

Application filed July 3, 1882. (No model.)

To all whom it may concern:

Be it known that I, JAMES MUIRHEAD, of Olneyville, in the county of Providence and State of Rhode Island, have invented certain new and useful Improvements in Water-Closets, of which the following is a full and correct description, reference being had to the accompanying drawings, forming a part of this specification.

10 In the drawings, Figure 1 shows a vertical section of the bowl and case, taken through the center and agreeing with the line *o o*, Fig. 2. Fig. 2 is a horizontal section, taken through the center of the case and agreeing with the line *x x*, Fig. 1.

A is the bowl, the upper part of which is of the usual shape; but the lower part is curved away to a horizontal position, and the end inserted in the end of the case B. This case is 20 made of cast-iron, or other suitable material may be used. A gate or valve, *a*, is placed in a vertical position in the case and supported on ways *i i* on the sides of the case, and upon which it slides back and forth, so as to open 25 or close the lower end of the bowl A. The gate *a* has a projecting flange, that covers the opening into the pipe *h* when the gate is closed, and also serves to prevent any of the contents of the bowl from passing in back of 30 the gate when opened and clogging up the mechanism. A ring of packing, *V*, of rubber or other suitable substance, is sprung into a groove in the face of the gate, to pack any little 35 inequalities in the end of the bowl that forms the valve-seat. A horizontal rocker-shaft, *d*, is placed across the case, moving in bearings in the sides of the case, one end of the shaft extending through to the outside to receive the wheel *d'*, by which the shaft is operated by means of the rod *o*, which is attached 40 to a stud in the wheel. The wheel is furnished

with a strap, *f*, and weight *z*, to assist in closing the gate *a*. To the middle of the shaft *d* is fastened the arm *t*, which is connected by the rod *g* to the gate *a* by pivoted joints.

45 The operation is as follows: By pulling up the rod *o* the shaft *d* is turned, and the arm *t* draws back the gate *a* to the position shown by the dotted lines in Fig. 1. This leaves a free passage for the contents of the bowl A to 50 pass down into the pipe *h*, and thence, by floating up the ball *C*, through the trap. At the same time the curved arm *w* raises the valve-stem *e* and allows the water to flow into the bowl through the pipe *r*. When the rod *o* is 55 pushed down again, the arm *t* carries the gate *a* forward, and as the arm *t* and the rod *g* come up into line with each other they form a toggle-joint, which exerts great pressure on the gate *a* to make it tight on its seat, and effectually prevents it from being opened by any 60 pressure in the bowl.

65 The side of the case B may be made removable, so that easy access may be had to the parts inside.

65 The vertical position of the gate and its seat prevents anything from remaining on them in the way of their closing tight. The pressure on the gate is easily exerted by means of the toggle-joint, and may be assisted by a weight 70 on the wheel, which at the same time prevents the gate from opening of itself.

75 What I claim as my invention, and desire to secure by Letters Patent, is—

The combination of the bowl A, case B, provided with ways *i i*, gate *a*, packing *V*, rod *g*, arm *t*, and shaft *d*, substantially as described, and for the purpose set forth.

JAMES MUIRHEAD.
